METHOD UTILIZING FORMATION RESISTIVITY MEASUREMENTS FOR DETERMINING FORMATION FLUID PRESSURES

Charles L. Blackburn, New Orleans, La., and Clarence E. Hottman and Robert K. Johnson, Houston, Tex., assignors to Shell Oil Company, New York, N.Y., a corporation of Delaware

Filed Sept. 22, 1962, Ser. No. 226,937
3 Claims. (Cl. 324—1)

This invention pertains to a method for determining reservoir fluid pressures and more particularly to a method utilizing resistivity logging techniques for determining when a well enters a section in which the fluid pressures exceed the hydrostatic head.

In many well drilling operations it is desirable to determine the fluid pressure of the various formations penetrated by the borehole. For example, when wells are drilled in formations having fluid pressures that exceed the hydrostatic head for the depth of the formation it is necessary to take certain precautions to prevent undue damage from the abnormally high pressure. These formations are commonly known as abnormally high pressure formations. The cost of drilling a 15,000 foot well with 5,000 feet of abnormal pressure section is frequently two to four times the cost of drilling a 15,000 foot well in a normal pressure section. This cost could be considerably reduced if it were possible to detect at what depth the borehole enters the abnormally pressured section. Knowing when the abnormal pressure section is penetrated would permit the use of normal drilling techniques until this penetration. The ability to use normal techniques for part of the well would considerably reduce the over-all cost of drilling the well. The added cost of drilling an abnormally pressured formation results in part from the increased cost of the drilling mud due to the requirement that it be heavier in order to contain the high pressures. The increased weight of the drilling mud results in a decrease in the drilling rate and more frequent fishing jobs to recover stuck drill pipe and increases the frequency of lost circulation. In addition to the increased costs of using heavier muds, costs are further increased by the necessity of employing heavier casing and additional strings of casing than are used in normally pressured formations.

In addition to the above it is desirable in many fields of petroleum exploration to know the fluid pressure of formations penetrated by a borehole. The present practice requires that a portion of the formation be isolated and then the formation pressure determined by use of various instruments. This procedure of course requires considerable equipment and time resulting in a large expense. Thus, in many cases where formation pressures would be useful they are not obtained.

Accordingly, it is the principal object of this invention to provide a novel method for detecting the fluid pressures of formations penetrated by a borehole.

Another object of this invention is to provide a unique method using resistivity logging techniques to determine fluid pressures of formations penetrated by a borehole.

A further object of this invention is to provide a novel method utilizing resistivity logging techniques to detect where a well penetrates an abnormally high pressured section prior to the penetration of a permeable reservoir formation.

The above objects and advantages of this invention are achieved by determining an electrical characteristic of the shale formations traversed by the borehole. The electrical characteristic may be resistivity with measurements preferably made at frequent intervals during the drilling of the well and a plot of the resistivity of the shale sections with depth being maintained. As the borehole enters the ab-

2

normally pressured formation the rate at which the resistivity increases with each increment of depth decreases from the rate exhibited in the normally pressured formations. At this point the resistivity decreases with respect to the value that would be predicted from the rate of change in resistivity in the normally pressured formations. The point at which the resistivity rate of change decreases indicates the penetration of the abnormally pressured section. Thus, it is possible to drill the portion of the well above the abnormally pressured section using normal drilling techniques and only the portion of the well which actually penetrates the abnormally pressured section will require the high cost special techniques. This will result in an over-all reduction of the drilling cost of the complete well.

The fluid pressures of the formations penetrated by the borehole can be determined from resistivity log data. It has been discovered that for many formations the fluid pressure of the formation is related to the resistivity of the formations. This discovery was made by making a direct comparison of measured formations pressure parameter to a resistivity parameter. Thus, it is possible to predict the fluid pressure of formations penetrated by the borehole.

The above objects and advantages of this invention will be more easily understood from the following detailed description of a preferred embodiment of the method when taken in conjunction with the attached drawing, in which:

FIGURE 1 represents a simplified block diagram of a resistivity well logging tool;

FIGURE 2 is a plot of the resistivity with depth for a well showing the change in resistivity as the well penetrates the abnormally pressured section;

FIGURE 3 is a plot of a resistivity parameter with the fluid pressure gradient in the normal pressured section;

FIGURE 4 is a curve showing the variation in resistivity with temperature in shale formations and in sea water solutions;

FIGURE 5 is a plot of the temperature corrected resistivity with depth for a well showing the change in resistivity as the well penetrates the abnormally pressured section; and

FIGURE 6 is a plot of a temperature corrected resistivity parameter with the fluid pressure gradient in the normally pressured section.

Abnormally pressured sections occur in many different geographical locations where it is desired to drill oil wells. One particular geographical location is the Texas-Louisiana gulf coast region of the United States that have tertiary shale formations of great thickness. These shale formations are usually deep water marine shales that contain few sand formations and are subjected essentially to a uniaxial compaction as a result of the compressive stress of the overburden.

In order for a shale formation to compact the fluids contained in the formation must be removed. The fluids can only be removed by flowing into sand formations or other permeable avenues of escape. Since the thick shale formations that occur in the gulf coast area have very few sand formations to act as avenues of escape the fluids are removed at a much slower rate than from thinner shale formations sandwiched between sand formations. This inability of the fluid to escape from the shale formations results in the creation of abnormal pressures within the formation.

The creation of abnormal pressures within a shale formation can be more easily understood by considering the following conception of a shale model. The shale model is formed from perforated metal plates which are separated by springs and water with the complete structure being enclosed within a cylindrical tube. The springs

simulate the communication between the clay particles while the plates themselves simulate the clay particles. Upon the application of pressure to the uppermost plate the height of the springs between the plates remains unchanged as long as no water escapes from the system. Thus, in the initial stage the applied pressure is supported entirely by the equal and opposite pressure of the water. As the water escapes from the system through the perforations in the plate the uppermost plate will move downward slightly and the springs will carry part of the applied load. As more water escapes the springs will carry additional load until finally the complete axial load will be borne by the springs and the system will reach a state of equilibrium.

The clay particles forming a shale formation undergo a similar movement to that described above for the model when subjected to a uniaxial compaction due to the overburden. All formations are subject to an axial compaction but more permeable formations reach equilibrium much faster than shale formations. The inability of shale formations to reach equilibrium results in the occurrence of abnormally high pressured shale and abnormally high pressures in the fluids contained in permeable rocks which are enclosed within such shales.

Referring now to FIGURE 1, there is shown a simplified diagram of an electrical logging tool. The tool consists of two electrodes 10 and 11 that are lowered into a borehole. The electrode 10 is coupled by means of a conductor 13 to a generator 14 located at the surface with the generator 14 being coupled to a ground 15. Thus the generator 14 will induce a circulating electrical current in the formation surrounding the borehole 12. The electrode 11 is coupled by means of a conductor 16 to a recorder 17 located at the surface.

The recorder 17 measures the potential existing between the electrode 11 and ground and this potential will be related to the resistivity of the formation adjacent the electrode 11. The recorder 17 can record the information in various forms with information being normally recorded in ohm meters. The recorded information will be recorded in relation to the depth of the electrodes in the wellbore 12. Of course, in actual practice the electrodes are disposed on an instrument that is lowered into the wellbore at the end of a logging cable and the information transmitted to the surface where it is recorded.

A normal resistivity log that is provided by various logging companies is referred to as a short normal electrical resistivity log. This log is particularly adapted for use with this invention since it is not normally necessary to apply any borehole correction for the conditions usually encountered in abnormally pressured sections. While this type of resistivity log is desirable other types of electrical logs may be used, as for example induction, resistivity or normal resistivity. The shale resistivity (R_{sh}) as measured on a short normal electrical log is dependent on four rock variables: porosity (ϕ), cementation factor (m), temperature (T) and resistivity of the fluid saturating the shale formation (R_w). The functional relations between these various factors can be expressed symbolically by the following formula:

$$R_{sh} = f(m, R_w, \phi, T) \quad (I)$$

In the normally pressurized tertiary sections of the gulf coast of the United States, three of the variables—porosity, cementation and temperature—can be expressed as functions of depth, as follows:

$$\phi \sim Z^{-1} \quad (II)$$

$$m \sim Z \quad (III)$$

$$T \sim Z \quad (IV)$$

In addition to the above, the effect of the saturating fluids on resistivity remains essentially constant with respect to depth. From the above, it is readily apparent that whether the shale resistivity increases or decreases

or remains constant as a function of increase in depth is dependent upon the rate of change of the dependent variable in Equation I above.

Referring now to FIGURE 2, there is shown a plot of the resistivity with respect to depth for a well drilled that as the well enters the top of the abnormal pressure in the gulf coast area. From this plot it is easily seen that the resistivity decreases rapidly. The data, plotted in FIGURE 2 is uncorrected for the above variables and from this data it is seen that the variables do not vary linearly with depth but as some other function of depth.

The well illustrated in FIGURE 2 was drilled using normal techniques and obtaining resistivity logging data at the various intervals. These data were then plotted as shown in FIGURE 2 and a determination made of the expected rate of increase in resistivity with depth. As the well was drilled deeper the rate of increase in the resistivity was noted and the point at which this rate of increase changed or, as shown in FIGURE 2, actually reversed and became a decrease in resistivity was used as the top of the abnormally pressured section. As shown in the data in FIGURE 2, this occurred at approximately 11,000 feet. At this point, the procedures required for drilling in abnormally pressured sections were then instituted and the well deepened to its desired depth.

From the above it can be seen that the first 11,000 feet of the well could be drilled using normal techniques and only the remaining few thousand feet would require the techniques used in abnormally pressured sections. Thus, a considerable reduction in the total cost of drilling a well would be effected. This cost results both from the reduction in the equipment and materials required and the more rapid drilling of the upper portions of the well.

Referring now to FIGURE 3, there is shown a plot of the shale resistivity parameter plotted against fluid pressure gradient for the sands that are enclosed by the various shale formations penetrated by the well whose resistivity curve is shown in FIGURE 2. The resistivity parameter plotted in FIGURE 3 is as follows:

$$\left[\frac{(R_a N - R_a A)}{R_a N} \right] \times 100$$

In this formula $R_a N$ is the apparent shale resistivity that is indicated by extrapolation of the resistivity curve for the normally pressured section of the well to the depth Z_a , and $R_a A$ is the apparent resistivity indicated by the log of the abnormally pressured section at depth Z_a . From this curve it is possible to determine the pressure gradient for any particular position or depth of well and thus the net weight required during drilling operations to contain the pressures that are likely to be encountered. This permits one to tailor the mud used in drilling to the actual conditions that exist in the well. This ability to tailor the mud to the requirements results in a saving since the use of excessive mud weights can be reduced.

As explained above, the resistivity for the well shown in FIGURES 2 and 3 is not a linear relationship with depth and thus it is desirable to correct a measured resistivity to obtain a linear relationship. It has been discovered that if the measured resistivities are corrected for temperature alone one will obtain a substantially linear relationship between the logarithm of the measured resistivity and depth. A typical curve for correcting measured resistivities is shown in FIGURE 4. One of the curves shown is for correcting resistivities in shale formations, while the second curve is for correcting resistivities measured in saline solutions. Using this curve to correct the resistivity measurements shown in FIGURE 2 and then replotted the information, one would obtain a curve similar to that shown in FIGURE 5. It will be noted from the curve shown in FIGURE 5, that the relationship between the logarithm of shale resistivity versus

depth is substantially a linear relationship. Thus, the conversion of the resistivity to a linear relationship to depth provides an easy means for projecting the resistivity in the normal pressured zones to obtain the data required for plotting resistivity parameters against fluid pressure gradients. Using the data from FIGURE 5, one can obtain the curve shown in FIGURE 6 which is substantially similar to that shown in FIGURE 3.

Using the curve plotted in FIGURE 5, one could drill a well in the same manner as that described above with relation to FIGURE 2. Accordingly, one would drill using normal techniques until a depth was reached at which the rate of increase in resistivity decreased. This decrease in the rate of increase in resistivity would then indicate the top of the abnormally pressured section. At this point, of course, one would institute the techniques required for drilling abnormally pressured sections.

While this invention has been described with relation to two separate techniques it should be appreciated that it is susceptible to many modifications and changes within its broad spirit and scope. For example, while it is preferable to use the amplified short normal electrical resistivity logs one could also use other types of devices that yield formation resistivity. While this is possible, care must be exercised in using any resistivity log in order to eliminate as many sources of error as possible.

We claim as our invention:

1. A method for detecting the fluid pressure gradient of a permeable subsurface earth formation penetrated by a borehole, said method comprising: measuring the individual resistivities of the shale formations penetrated by the borehole; recording the resistivities with relation to the depth of the point of measurement in the borehole; continuing to measure said resistivities as said borehole is drilled; and measuring the difference between said recorded resistivities in abnormally pressured shale formations penetrated by the borehole and a projection to the depth of the abnormally pressured shale formations of a measured resistivity of the trend with depth of the

resistivities in normally pressured shale formations penetrated by the borehole to determine the fluid pressure gradient of an adjacent permeable subsurface earth formation.

2. A method for measuring the fluid pressure gradient existing at a selected depth below an abnormally pressured shale formation comprising:

measuring the depth at which the borehole enters an abnormally pressured shale formation;
measuring the trend with depth of the individual resistivities exhibited by shale formations encountered above said abnormally pressured shale formation;
measuring the resistivity of a shale formation at a selected depth encountered below said abnormally pressured shale formation;
determining the difference between the resistivities exhibited at the selected depth by, respectively, a projection to the selected depth of the trend of resistivities exhibited by the shale formations encountered above said abnormally pressured shale formation and the measured resistivity;
measuring the amount of fluid pressure gradient from preplotted values of fluid pressure gradient in relation to the difference in resistivities that corresponds to the difference between the resistivities exhibited at the selected depth.

3. The method of claim 2 in which the trend with depth of said resistivities is measured from logarithms of resistivities that are corrected for the effects of temperature.
